FIGURINE

Carl Romanelli, Los Angeles, Calif.

Application January 10, 1949, Serial No. 160

Term of patent 3½ years

(Cl. D29—23)

To all whom it may concern:

Be it known that I, Carl Romanelli, a citizen of the United States of America and a resident of Los Angeles, county of Los Angeles, State of California, have invented a new, original, and ornamental Design for a Figurine, of which the following is a specification, reference being made to and including the drawing as forming a part thereof.

In the drawing:

I claim:

The ornamental design for a figurine, substantially as shown.

CARL ROMANELLI.
